UNITED STATES PATENT OFFICE

2,624,878

STAPLING MACHINE

Herbert W. Marano, Brooklyn, N. Y., assignor to
 Wilson Jones Company, Chicago, Ill., a corporation of Massachusetts

Application April 27, 1950, Serial No. 158,462

6 Claims. (Cl. 1-3)

1

The present invention relates to stapler or tacking devices. In particular, the present invention relates to a stapler of the hand-grip type, which may be held entirely within one hand for actuation, either by forcing one component against the other, or by resting one component thereof on a suitable support and hand-forcing the other component thereagainst.

The main object of the present invention is the provision of a device of the character described wherein the staple advancing pusher is automatically locked in retracted position during the staple loading operation so as not to interfere with the staple loading, and is automatically released for advancing pressure against the staples when the loading thereof is completed.

Still another object of the invention is the provision of a device of the character described including a staple pusher, which staple pusher is normally slidably flatly along a suitable support, but, on retraction to permit staple loading, is rockable from the flat position and locked out of engagement with the staples.

Another object of the present invention is the provision of a hand stapler of the character described which has substantially increased staple capacity in relation to length.

Other and further objects of the present invention will in part be obvious, and in part specifically pointed out in the following description of an illustrative embodiment thereof.

In the drawings annexed hereto and forming a part hereof,

Figure 1 is a longitudinal vertical section through one form of stapler device constructed according to and embodying the present invention;

Figure 2 is an enlarged similar section of the hinged rear end of the device, illustrating the staple pusher in retracted and locked position;

Figure 3 is an enlarged similar section of the front end of the stapler cover, in staple driving position;

Figure 4 is a section on the line 4-4 of Figure 1;

Figure 5 is a section on the line 5-5 of Figure 1;

Figure 6 is a part plan and part horizontal section of the staple housing, trackway and staple pusher assembly;

Figure 7 is a section on the line 7-7 of Figure 1; and

Figure 8 is an exploded perspective view of the components of a stapler constructed according to and embodying the present invention.

2

The device of the present invention, indicated generally by reference numeral 10, comprises a base plate 12, a cover 30 including a cover guide 50, and a staple magazine assembly, all of which elements are pivotally pinned together at one end thereof.

Base plate 12 comprises an elongated member having an anvil 14 secured to its forward end as by rivets 16, 16. Anvil 14 may be fixed to base 10 12 as shown, but within the present invention may be shiftable lengthwise of base 12 and may have more than one set of staple guide grooves, as 18, 18, to bend the staple legs inwardly or outwardly as desired, this being conventional in the art. The sides of base 12 are bent upwardly progressively from the front end 20 thereof towards the rear 22, to form side walls 24, 24 of increasing height, walls 24, 24 being extended rearwardly past end 22 as at 26, 26, the extensions being 20 transversely apertured as at 28, 28, for pivoting purposes.

Cover 30 is substantially as long as base 12, and is provided with a downwardly depending skirt wall 32, 32, transversely apertured at the rear 34 25 thereof for pivoting, as at 36. A drive member 38 of flat spring steel is provided and secured to the underside of cover 30 as by rivets 40, 40, member 38 having an integral downwardly projecting staple driver component 42 at the forward end thereof and an integral rearwardly and downwardly angled spring arm 44 at the rear thereof.

A cover guide 50 is provided, comprising a pair of spaced side bars 52, 52 connected by a narrow integral cross strip 54 near the front, and an integral cross platform 56 at the middle. Bars 52, 52 are spaced apart as to fit inside cover 30, and they are transversely apertured at the rear ends, as at 58, 58 to pivot with cover 30, apertures 58, 58 lining up with apertures 36, 36 in cover 30. 35 Staple driver 42 is notched along its upper sides, as at 60, 60, to a depth sufficient to receive fingers 62, 62 projecting forwardly thereof from the top of side bars 52, 52. Thus, when cover 30 and cover guide 50 are pivoted about a common center, 40 and fingers 62, 62 fitted into notches 60, 60 (see Figures 1 and 4), the pressure of spring arm 44 against platform 56 locks guide 50 within head 30, since the projections 62, 62 extend well past staple driver 42 and are trapped within the 45 notches 60, 60.

The staple magazine assembly includes housing 64, staple support trackway 66, staple pusher 68 and a staple feed spring 70, the latter being mounted about a locating and guide rod 72 50 55 trapped within trackway 66, lengthwise thereof.

Housing 64 comprises a floor portion 74 and upstanding side walls 76, 76 and an upstanding front wall 78. Sides 76, 76 are extended rearwardly of floor 74, as at 80, the extension being horizontally apertured as at 82, 82 for pivoting purposes. Wall 78 is notched, adjacent the top thereof, as at 79, to limit downward movement of cover guide 50 during a stapling operation. Staple driver blade 42, locked to cover guide 50, as guide 50 pivots into housing 64, slides against the inner aspect of housing wall 78, and is guided thereby in its straight line downward movement.

As seen in Figure 7, base 12, housing 64, cover guide 50 and cover 30 are pivotally connected at their rear ends, as by a rivet 84 passing through registering apertures 28, 82, 58 and 36, the respective elements being nested as shown. A base spring leaf 86 is secured to the upper surface of base 12 by rivets 88, 88, the free end 90 thereof angled rearwardly and upwardly bears against the underside of housing floor 74 to resist, to some degree, movement of housing 64 towards base 12. Within housing 64 is disposed the staple support trackway 66, including pusher 68 of the present invention.

Trackway 66 comprises a floor 92 and upstanding side walls 94, 94, the upper edges 96, 96 of which are flanged outwardly flatly and at right angles to walls 94, 94, as at 96, 96, flanges 96, 96 being so spaced apart as to permit conventionally sized staples to rest flatly thereon, with the staple legs extended downwardly. As seen in Figures 4, 5 and 6, the overall height of walls 94, 94 and flanges 96, 96 is such as to equal the length of conventional staple legs, as 98, the base 100 of the staples resting flatly atop flanges 96, 96. Floor 92 is cut away behind front wall 78, as at 102, to permit passages of staples therethrough under the influence of staple driver 42. Floor 92 is bent up adjacent the front end thereof as at 104, and the rear end thereof is bent up as at 106, the bendings defining parallel lugs at opposite ends of the trackways and having aligned transverse apertures 108, 110 therethrough respectively. Trackway 66 is disposed within housing 64, atop floor 74, positioned so that the front end of the flanged portion is spaced one staple's thickness from the inner aspect of housing wall 78, as indicated at 112; the spacing at 112 being in vertical alignment with opening 102 in the floor of housing 64.

Staple pusher 68 comprises a flat body portion 114 with depending side walls 116, 116. A wing 118 is struck out from body 114 and bent downwardly at right angles thereto. A second wing 120 is struck out from body 114 and bent upwardly therefrom at right angles thereto. Depending wing 118 is apertured, as at 122 to permit the passage of rod 72 therethrough, opening 122 being larger than the diameter of rod 72. The forward ends of sides 116, 116 are provided with integral inwardly directed and extended spring fingers 124, 124, and the rear ends of sides 116, 116 are provided with integral, inwardly and rearwardly directed spring fingers 126, 126. These two pairs of inturned fingers serve to retain pusher 68 slidably and flatly atop trackway 66, while permitting a rocking or tilting action thereof at one portion of the trackway. It is to be noted that while the rear fingers 126, 126 are substantially the full height of sides 116, 116, the front fingers 124, 124 are formed some little distance below body 114 thereby providing a space, as 128 between body 114 and fingers 124, 124 (see Figure 2). The rear ends of flanges

5

96, 96 are bent downwardly, as at 97, 97, the bending limiting rearward movement of pusher 68.

Referring to Figure 8, it will be seen that flanges 96, 96 are notched as at 130, 130, near the rear end thereof. In assembling trackway 66, pusher 68 is slid over flanges or rails 96, 96 from the front thereof. The spring 70 is then threaded on rod 72, and the leading end of the rod passed through wing aperture 122 of pusher 68. The leading end of rod 72 is then passed through aperture 108 in lug 104, and the rear end of rod 72 passed through aperture 110 in lug 106. The projecting ends of rod 72 are then upset, as at 132, 132 to lock the parts together, and the assembly is then secured, as by spot welding at 134 (see Figure 5) within housing 64 as above detailed.

Cover 30 and cover guide 50 are assembled, and fitted within the rear walls of housing 64, and thence between extensions 26, 26, and the parts pinned together for pivotal movement by rivet 84. As will be obvious, cover 30 and cover guide 50 will pivot substantially as one, while relatively swingable through the degree of arc permitted by fingers 62, 62, along notches 60, 60 in ram 42. Housing 64 is swingable with respect both to base 12 and the cover and guide assembly, but I provide means to releasably lock housing 64 to the cover and guide. These means comprise upwardly extended wings 136, 136 (Figures 5 and 8) formed atop side walls 64, 64, wings 136, 136 being transversely apertured as at 138, 138, these apertures lining up with outwardly bumped projections 140, 140 on the sides of bars 52, 52 of guide 50, the interfit of the bumpings in apertures 138 spring holding the parts together against disengagement (except for permitting the insertion of staples into the magazine) during ordinary use of the device. As so located, there is sufficient space between the underside of guide bars and the top of flanges 96, 96 to permit sliding movement of pusher 68 under the influence of spring 70. The relative pivoting movement of guide 50 towards housing 64 is limited by fingers 62, 62 resting atop notches 79, 79 in housing wall 78 (Figure 4).

To load a supply of staples onto trackway 66, within housing 64, the cover and guide assembly 50 is released from the engagement of lugs 140, 140 in apertures 138, 138 (Figure 5) and swung away from housing 64, into the position of Figure 2, thereby exposing the interior of housing 64 and trackway 66 therewithin. Pusher 68 is then slid rearwardly on trackway 66 by manual pressure against upstanding wing 120, until the pusher passes notches 130, 130, this rearward movement being limited by downturned flange portions 97, 97. As fingers 124, 124 pass notches 130, 130, a tilting movement is developed on pusher 68 by compression of spring 70, due to the location of the points of action, and the front end of the pusher tilts upwardly and fingers 124, 124 raised above the level of notches 130, 130. Thus, on release of the moving force, fingers 124, 124 will be spring pressed against the forward edges of notches 130, 130, to hold the pusher 68 temporarily in that position and out of the way while a strip of staples is laid into housing 64 with the staple bodies 100, 100 lying flatly atop flanges 96, 96 and the staple legs 98, 98 projecting downwardly into the space between housing walls 76, 76 and flanges 96, 96. When the staple supply strip is thus positioned, cover 30 and guide 50 are swung, as a unit, over

against and onto housing 64. Pusher 68 is locked at the rear of the device, nearer the pivot point, and as it is contacted by the lower edges of guide side bars 52, 52, bearing against the top of pusher body 114, it will be retitled to force fingers 124, 124 down below flanges 96, 96, and out of engagement therewith, whereupon the normal expansile biasing of spring 70 will shift the pusher against the rear staple in the supply strip, forcing the staple strip forwardly until the first staple in the strip is urged against the inner aspect of housing wall 78, over opening 102, and in line with staple driver 42, as in Figures 1 and 4. Lug 104 serves as a stop to engage wing 118 on the underside of pusher 68, limiting the forward movement thereof.

To operate the device to drive a staple, cover 30 is forced downwardly towards and against base 12, against the normal biasing of spring leaf 90, pressing against the underside of housing 74. As spring 90 is overcome and flattened, cover 30, guide 50 and housing 74 approach base 12, at which time staple driver 42 moves downward behind wall 78 and through the channel opening 112, separating the leading staple from the strip and driving same against anvil 14.

The cover 30, guide 50, housing 64, trackway 66 and base 24 are all formed, as by stamping or otherwise of flat sheet steel. The parts are heat treated at locations where wear occurs, and the device, as a whole, may be brightly plated or otherwise treated to enhance its appearance.

With my trackway and pusher arrangement, it will be seen that the staple holding capacity of my device is substantially that of the length of the trackway, less the length of the pusher. The particular coil spring shown, which has a plurality of coils of different diameters, while operating quite well with my device, is not essential thereto, same being the subject of a copending patent application Serial No. 83,750, filed March 16, 1949, which matured into Patent No. 2,528,444 on October 31, 1950, and which was reissued under No. Re. 23,349, dated March 27, 1951. As will be readily appreciated from the foregoing, my device may also be used to drive staples without deforming the legs thereof, as the cover 30, guide 50, and housing assembly 74 may be swung away from and used independently of base 12. In view of the relatively small size it is possible to achieve with a stapler of the present invention, a chain C may, if desired, be linked to the end thereof, as in Figure 1, so that it can be hung on a suitable support.

Having now described my invention, what I claim and desire to secure by Letters Patent is:

1. In a stapling machine including a base, an upper member of inverted channel shape, and a staple driver blade projecting downwardly therefrom at the front end thereof, with the rear end of the upper member being pivotally supported on the base; the improvements comprising a lower member of channel shape open at the top and forming a magazine for staples, the rear end of the lower member being pivotally supported at the rear end of the upper member; a means at the front end of the lower member for retaining the staples; a staple supporting trackway disposed within the lower member and spaced from the sides thereof and from the staple retaining means; a pusher movably supported on the trackway for engaging the staples; yieldable means in the magazine to urge the pusher forward for moving the staples towards the retaining means; inwardly directed fingers on the opposite sides of

the pusher extending towards each other, the trackway at the rear thereof having detents for the fingers, means for tilting the pusher with its front end upwards of the trackway upon manual retraction thereof for engaging the detents by the fingers thereby preventing the pusher from being moved by the urging means; a driver guide between the cover and the upper member and interengaged with the cover to pivot therewith, the cover and the guide being manually separable from the lower member substantially simultaneously to expose the interior of said lower member and the pusher therewithin; and means on the driver guide for yieldably depressing the raised front portion of the pusher when the upper member and guide are moved downwardly thereby releasing the pusher for forward movement under action of the urging means.

2. A stapling machine as in claim 1, wherein the pusher comprises a base portion disposed atop the trackway and is provided with walls depending from the sides of the base, and the fingers extend inwardly below the trackway during movement of the pusher under the influence of the slide urging means.

3. In a stapling machine including a base, an upper member of inverted channel shape, and a staple driver blade projecting downwardly therefrom at the front end thereof, with the rear end of the upper member being pivotally supported on the base; the improvements comprising a lower member of channel shape open at the top and forming a magazine for staples, the rear end of the lower member being pivotally supported at the rear end of the upper member; a means at the front end of the lower member for retaining the staples; a staple supporting trackway disposed within the lower member and spaced upwardly of the bottom of the lower member and from the sides thereof and from the staple retaining means in the front thereof; a pusher movably supported on the trackway for engaging the staples; yieldable means in the magazine to urge the pusher forward for moving the staples towards the retaining means; fingers on the opposite sides of the pusher bent inwardly towards each other, the trackway at the rear thereof having detents for the fingers, means for tilting the pusher with its front end upwards of the trackway upon manual retraction thereof for engaging the detents by the fingers thereby preventing the pusher from being moved by the urging means, a driver guide between the cover and the upper member and interengaged with the cover to pivot therewith, means to limit movement of the cover and guide towards and away from each other, the cover and the guide being manually separable from the lower member substantially simultaneously to expose the interior of said lower member and the pusher therewithin; and means forming part of the driver guide for yieldably depressing the raised front portion of the pusher when the upper member and guide are moved downwardly thereby releasing the pusher for forward movement under action of the urging means.

4. A stapling machine as in claim 3, wherein the driver blade has notched sides up from the bottom thereof, and the driver guide has forwardly extending spaced apart fingers at the front thereof passing through the notches in the blade for interengagement therewith.

5. A stapling machine as in claim 3, wherein yieldable means are provided between the cover

and the guide to urge them apart, said means comprising a leaf spring.

6. In a stapling machine including a base, an upper member the rear end of which is pivotally supported on the rear of the base, and a staple magazine between the base and upper member, the rear end of which magazine is pivotally supported on the rear of the base, the free ends of said base, magazine and upper member being separable at the unconnected ends; wherein the magazine is of channel shape open at the top with means at the front end thereof for retaining the staples; wherein a U-shaped member is secured within the magazine with the upper ends of the arms of the U-member bent over and outwardly to form a staple supporting trackway, the edges of which platform are spaced from the sides of the magazine and the front of which trackway is spaced from the staple retaining means at the front of the magazine whereby staples can move within the magazine along the trackway and towards the retaining means; wherein a staple pusher is disposed atop the trackway, the pusher comprising a body portion resting atop the trackway, walls depending from the sides of the trackway and fingers on said walls at the front thereof bent inwardly under the trackway; wherein

10

15

20

25

yieldable means are provided in the magazine between the arms of the U-member to urge the pusher forward for moving staples towards the retaining means; and wherein detents are provided on the trackway towards the rear thereof for releasably engaging and retaining the pusher and preventing the pusher from moving under the influence of the yieldable means when the pusher is manually retracted and raised causing the fingers thereon to engage the detents, thereby to provide access to the front of the trackway for loading staples thereonto.
